UNITED STATES PATENT OFFICE

DAVID RAY KOONTZ, OF SALISBURY, NORTH CAROLINA, ASSIGNOR OF ONE-HALF TO
JAMES D. DORSETT, OF SPENCER, NORTH CAROLINA

LOW WATER ACTUATED MEANS FOR STEAM GENERATORS

Application filed December 11, 1930. Serial No. 501,683.

This invention relates to a low water actuated means for a steam generator and comprises means whereby the same may be attached to a steam generator to cause steam 5 to be led from the generator to a low water alarm when a predetermined lowness of water has been reached in the generator so as to allow steam to pass into the low water actuated mechanism to expand the same and 10 to thereby open a valve to allow steam to pass through to an alarm and also means are provided whereby a jacket is mounted around the expansion member to protect the same from variation in temperature and also 15 to receive water from the water system as the water is passed into the steam generator to quickly cool the expansion member to cause the valve which has been opened by the expansion to be closed.

20 This invention is adapted to be operated simply as a low water alarm or can be used in connection with the mechanism disclosed in my co-pending patent application, Serial Number 483,307 which was filed in the United 25 States Patent Office on September 20, 1930 in which application, means are shown for using the steam which is allowed to escape from the low water alarm mechanism to automatically start an injector or a pump or 30 both if desired, and it is an object of this invention to substitute the low water actuated mechanism shown and described in this application in lieu of the low water alarm mechanism shown in the application above 35 referred to by serial number so that not only can this low water actuated mechanism be used as an alarm, but also to actuate the means for replenishing the supply of water in the generator as shown in said pending application.

40 Some of the objects of my invention having been stated other objects will appear as the description proceeds when taken in connection with the accompanying drawings in 45 which—

Figure 1 is a side elevation of a portion of a steam locomotive showing my invention applied thereto;

50 Figure 2 is a side elevation partly in cross-section showing the low water actuated means

in an enlarged scale from that shown in Figure 1;

Figure 3 is a top view of Figure 2;

Figure 4 is a cross-sectional view taken along the line 4—4 in Figure 2; 55

Figure 5 is a view of the lower right-hand portion of Figure 2 with certain of the parts removed for sake of clearness.

Referring more specifically to the drawings the numeral 10 indicates the boiler or 60 steam generating portion of a locomotive or any other steam generating unit which has a conventional cab 11 and threadably secured in the top portion of the boiler 10 is a member 12 which has a vertically disposed passageway 13 therein to which is secured in the lower end thereof a pipe 14 which leads downwardly into the boiler to a point below the normal water level line in the boiler and immediately above the danger water level line 65 15 which is indicated in Figure 1. This member 12 also has a vertically disposed port 16 therein which communicates with a transversely disposed port 17 into which is threadably secured a member 18 and in this passage- 70 way 17 a compression spring 19 is mounted and inside of this compression spring is mounted a valve and valve stem 20 which seats as at 21 and the stem extends outwardly where it is engaged by another stem 22 which 75 is slidably mounted in the nut 23 which is threadably mounted in the end of member 18. This member 18 has a vertically disposed port 24 which has secured in the lower end thereof a nipple 25 with an elbow 26 secured thereto and a pipe 27 leading therefrom. This pipe 27 is adapted to lead to a cylinder 28 which is more specifically described in my co-pending application, Serial Number 483, 80 307, above referred to. The member 12 has 85 a projection 29 on one side thereof in which is adjustably mounted a rod 30 by means of nuts 31 and 32 on opposite sides thereof which rod is threadably mounted in the lower 90 end of a support 33. The support 33 projects upwardly and has a pin 34 secured thereto which serves as a pivot point for bell- 95 crank lever 35 which has one end thereof pivotally secured as at 36 to a member 37 which is threadably secured on the upper end 100

of member 38, member 38 being preferably a brass pipe or any other material having a suitable co-efficient of expansion. This member or pipe 38 is threadably secured at its 5 lower end in the upper enlarged end of port 13 in member 12. Closely surrounding the member 38 and spaced some distance therefrom is a jacket member 39 which is threadably secured to member 12 at the lower end 10 thereof and forms a sliding fit with the member 38 at the upper end thereof. This said jacket has a pipe 40 leading into the upper end thereof from the upper end of container 41 and a pipe 42 leads into the bottom of container 41, said pipe leading from pipe 43 which is the supply pipe leading from the injector or pump, which is not shown, into the boiler so that when the injector or pump is automatically started by this low water 15 mechanism that a portion of the water will pass upwardly to the container 41 and thru pipe 40 into the space between jacket 39 and member 38 to quickly cool the same to cause the valve 21 to be closed. This container 41 20 has a leak 44 extending from the bottom portion thereof which is connected to a drain pipe 45 and also connected to this drain pipe 45 is a leak 46 which is connected to port 47 which communicates with the space between 25 members 38 and 39 so that the water in the jacket 39 will be drained when the operation of pumping or injecting water into the generator has ceased.

The bell-crank lever 35 has a cavity there- 30 in in which a compression spring 47 is mounted, and the other end of this compression spring fits against the support 33 so as to normally hold the bell-crank lever 35 in the position shown in Figures 1 and 2. The 35 lower end of this bell-crank lever 35 is adapted to engage the end of member 22 to open valve 21 when steam is allowed to pass into member 38.

Passageway or port 17 which has previous- 40 ly been described as having the port 16 passing thereto, also has a port 48 leading laterally therefrom which is normally closed by a tap 49, the purpose of this additional 45 port being that if desired a supply of steam from the steam turret or any other suitable 50 source can be led to this port 48 by removing tap 49 and connecting a suitable pipe thereto- 55 into so that steam can be led through the de- vice from any other suitable source if de- 60 sired instead of allowing the steam to pass into the low water alarm means through port 16.

The steam passing through pipe 27 can be 65 led through cylinder 28 and then through pipe 27a to the low water alarm whistle 50 if desired or in case the mechanism of cylinder 28 is not used, then the pipe 27 can be led directly to the low water alarm 50 which is a 70 whistle, or if desired it is evident that any

other suitable alarm means can be actuated by the steam passing through pipe 27.

In case the cylinder 28 which is more spe- 75 cifically described in my co-pending patent application above referred to, should be used in connection with an injector, then pipe 51 would be led to the steam turret through a manual valve and pipe 52 would also be led to the steam turret through a manual valve and pipe 53 would be led to the bottom of the overflow valve of the injector and pipe 54 would be led to the top of the valve in the injector which when opened allows steam to be passed through the injector to suck water into the boiler and pipe 55 would be used as 80 a drain pipe.

In case the above described mechanism should be used in connection with the conventional water pump on a steam generating plant such as a railroad locomotive, then the pipe 51 would be led to the steam turret and 85 52 would serve as a drain while 53 would lead to the bottom of a valve for opening the same to admit steam to the steam water pump, and 54 would lead to the top of said valve while 55 would be a drain pipe.

The method of operation of the mecha- 90 nism above described is as follows:

With the mechanism installed as shown in 95 Figure 1 it is evident that when the water in the generator 10 sinks to the point indicated by the dotted line 15 that steam will be allowed to pass through pipe 14 into the member 38 and expand the same. This will 100 push point 36 upwardly and due to the great compoundage between the two ends of the bell-crank lever with relation to pivot point 34, the lower end of said bell-crank lever 35 will push member 22 inwardly and this will 105 open valve 21 and steam will pass from the interior of the generator through pipe 27 and into cylinder 28 to automatically actuate the injector or the pump as the case may be and also pass the steam through pipe 27a to 110 low water alarm 50. At the same time the water passing through pipe 43 from the pump or the injector into the generator will be under great pressure and this will cause a 115 small portion of water to be forced upwardly through pipe 42 into retarding container 41 and fill the same, but while filling the same water will be leaking through pipe 44 and pipe 45, but on account of the fact that the intake of water into tank 41 will be much 120 greater than the outgo this will fill at a pre- determined time and water will pass from the upper portion of container 41 through pipe 40 into the space between jacket 39 and the expansion member 38 and cool the expansion member and cause the parts to assume the position shown in Figures 1 and 2 and allow valve 21 to close and cause the steam to 125 stop passing through pipe 27 and to low water alarm 50 and to the cylinder 28 because 130

this cylinder and its associated parts will already have been actuated to automatically start the pump or injector as the case may be. The water passing into the space between jacket 39 and expansion member 38 will gradually leak through port 47 and pipe 46 into drain 45 and the parts will assume a position ready for instant operation when another low water level occurs in the system.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. In a low water alarm for steam generators, an expansion member adapted to be in fluid communication with the interior of the generator, a valve having a passageway for communication with the interior of the generator and means for normally closing the valve, a bell crank lever having one end thereof connected to the expansion member and the other end thereof normally in close proximity to but disconnected from said valve, means independent of the expansion member for pivotally supporting the bell crank lever intermediate its ends, a jacket surrounding the expansion member, means for supplying a cooling fluid between the expansion member and the jacket.

2. In a low water alarm, a boiler, a thermostatically actuated expansion element, a fluid connection between the said boiler and the expansion element, means controlled by said expansion element for forcing water into the boiler, a jacket surrounding the expansion element and forming a space between the expansion element and the jacket and means for forcing a cooling fluid into said space while water is being forced into the boiler, said means operable by said expansion element including a member having a passageway for leading steam out of the boiler, a normally closed valve in said passageway, a support, a bell crank lever pivoted intermediate its ends on said support, a pivoted connection between one end of said lever and said expansion element, the other end of said lever being removed normally from said valve and being adapted to engage and open said valve when moved by the expansion element.

3. In a steam generator, a device adapted to be operated by steam from said generator when a predetermined degree of lowness of water occurs in the generator, said device comprising a connection piercing the shell of the generator and extending below the normal water line, an expansion element secured in said connection and being in fluid communication with the interior of the gen-

erator, an adjustable support secured to said connection, a bell crank lever pivotally secured intermediate its ends to the said support, means for securing the shorter end of the lever to the expansion element, a valve in said connection and having fluid communication with the interior of the generator, a valve stem associated with said valve and projecting in close proximity to the longer free end of the bell crank lever, said valve being adapted to be opened when said expansion element moves said bell crank lever in one direction, a jacket surrounding the expansion element in spaced relation thereto and having its lower end secured in said connection and slidably engaging the expansion element near its upper end and means for forcing water between said jacket and said expansion element after said valve has been opened by said lever.

4. In a combined low water alarm operating means for water forcing means for steam generator, an expansion element in fluid communication with the interior of the generator and having a passageway for steam leading from the generator, a normally closed valve in said passageway, means associated with said expansion element and said valve for opening the valve when steam passes into the expansion element, a jacket surrounding said expansion element in spaced relation thereto and means for passing a cooling fluid between said jacket and said expansion element after the same has been expanded to sound the low water alarm and start the said water forcing means.

5. Means for automatically replenishing the supply of water in a steam boiler and sounding a low water alarm comprising an expansion element in fluid communication with the interior of the boiler, means operable by the expansion element for actuating the water replenishing means, a jacket surrounding the expansion element and forming a space therearound, and means communicating with the water replenishing means for forcing water into said space to cool the expansion element.

6. In a steam generator having a low water alarm and also having means for forcing water into the generator, other means for allowing steam to be conducted from the generator to the forcing means to render the same operative, means for conducting said steam from the forcing means to the low water alarm after the forcing means has been rendered operative, said other means comprising an expansible member in fluid communication with the steam in the generator, a jacket enclosing the expansible member, a bell crank lever pivotally mounted intermediate its ends and having one of its ends connected to the expansible member and having its other end adapted to control the flow of steam from said other means to the

- forcing means, and means for passing a cooling fluid between said jacket and the expandible member when the forcing means are operated.
- 5 7. Means for automatically forcing water into a steam generator when the water level therein falls below a predetermined point, said steam generator being provided with conventional water forcing means, comprising:
- 10 a hollow expandible element in fluid communication with the interior of the generator, control means for the water forcing means, a steam connection between said generator and said control means and having
- 15 a normally closed valve therein, means operable by the expandible element for opening said valve when the water level sinks to a predetermined point in the generator to allow steam to enter said expandible element, a
- 20 jacket surrounding said expandible element providing a space between the interior of the jacket and said expandible element, a reservoir having communication with the interior of said jacket at its upper and lower
- 25 portions, a drain pipe in said lower connection, means for conducting water from the water forcing means into said reservoir from whence the water is adapted to flow from the top of the reservoir when filled into said
- 30 space between said jacket and said expandible element to cool said expandible element to cause said valve to render inoperative the water forcing means.

In testimony whereof I affix my signature.
